UNITED STATES PATENT OFFICE.

ALEXANDER J. McMULLEN, OF MILWAUKEE, WISCONSIN.

AUTOMATIC STOKER FOR LOCOMOTIVES.

1,017,682.

Specification of Letters Patent.

Patented Feb. 20, 1912.

Application filed April 6, 1911. Serial No. 619,333.

To all whom it may concern:

Be it known that I, ALEXANDER J. McMULLEN, a citizen of the United States, and resident of Milwaukee, in the county of Milwaukee and State of Wisconsin, have invented certain new and useful Improvements in Automatic Stokers for Locomotives; and I do hereby declare that the following is a full, clear, and exact description thereof.

The object of my invention is to provide a simple, economical and effective automatic feeder and stoker for locomotive furnaces, its construction and arrangement being such that coal is discharged from the tender into a crusher, where it is broken to a convenient size and thereafter delivered from said crusher by means of an endless conveyer to a hopper disposed in juxtaposition to the furnace door opening, through which hopper it is delivered to the grate by movement of a reciprocative stoker bottom.

With the above object in view the invention consists in what is herein shown, described and claimed.

In the drawings Figure 1 represents, a longitudinal sectional elevation of the rear end of a locomotive and forward end of a tender equipped with an automatic stoker embodying the features of my invention; Fig. 2, a fragmentary plan view of the same partly in section, as indicated by line 2-2 of Fig. 1, and Fig. 3, a transverse sectional view of the stoker hopper mechanism, the section being indicated by line 3-3 of Fig. 2.

Referring by characters to the drawings, 1 represents a locomotive tender having the usual coal compartment which is provided 40 with a forwardly inclined bottom section 2 and an upwardly inclined hinged section 5. The hinged section 5 is provided with a feed opening 3 that is controlled by a sliding door 4 through which coal is delivered to a 45 crusher housing to be hereinafter described. The bottom section 5 is locked in its normal position by bolts 6 which engage the side walls of the tender and said bottom section is designed to be swung down in 50 an emergency whereby access may be had to the coal compartment in case of a temporary disarrangement of the stoker mechanism, in which case the crusher housing heretofore mentioned is detached from the 55 tender, whereby clearance is had to permit the hinged section 5 to drop to a horizontal

position. The hinged section 5 of the compartment flares upwardly from the inclined bottom section thereof whereby a pocket is formed for the coal and at the same time 60 clearance at the front end of the tender and under the door 4 is provided for the location of the crusher. By this arrangement the crusher can be placed under the forward end of the tender without appreciable waste 65 of space.

Secured to the floor of the tender directly under the feed opening 3 is a crusher housing 7 provided with an adjustable crusher-member 8 and a vibratory member 9, which 70 member is actuated by a shaft 10 that is provided with an eccentric 11, which eccentric, in conjunction with a strap, operates the vibratory member 9 by means of its engagement with toggle links 12. The strap 75 carried by the eccentric 11 depends therefrom and is notched out for the reception of the opposite ends of the links 12, the links being horizontally disposed. The outer ends of one of the links is fulcrumed to the 80 side walls of the housing 7 and the outer end of the opposite link is hinged to the vibratory crusher member 9. Thus when the high portion of the eccentric reaches a point opposite to that at which it is shown 85 in Fig. 1 the said strap is lifted whereby the inner ends of the links rise and tend to straighten out causing an inward crushing movement of said member 9. When the toggle links are buckled in the position 90 shown in the drawing the distance between their fulcrum points is shortened due to the weight of member 9, which weight brings said member back to its normal position and opens the mouth between it and the fixed 95 crusher member.

Journaled in the lower portion of the housing 7 is a shaft 13, which shaft is driven from the crusher shaft 10 by a link belt and sprocket gear connected thereto. Trunnioned 100 upon the shaft 13 is an elevator frame 14 which projects upwardly with its discharge end terminating within the cab portion 15 of a locomotive, the said discharge end being provided with an idle shaft 16 carrying sprocket wheels 17 that co-act with similar sprocket-wheels 18 which are carried by the shaft 13. Mounted upon these sets of sprocket-wheels is an endless link belt 105 conveyer chain 19 having suitable lugs 20. The discharge end of the conveyer frame 14 is loosely supported upon the fixed wall 21

2
of a hopper, which fixed wall is rigidly secured to a frame 22. The side walls 23 of the hopper are preferably in hinge connection with the frame 22, being held in their upright position by downturned ends of a detachable strap 24. Mouth sections 23^a of the hopper side walls are preferably rigidly secured to the frame 22 and, as shown, are adapted to project into the feed opening 25 of the locomotive fire-box 26, which fire-box is provided with the usual grate. The frame 22 is provided with ways 27 for the reception of rail extensions 27^a of a reciprocative box-like bottom 28, the outer 15 end of said bottom carrying a stoker-head 29 which serves to level off the coal as it is delivered by the reciprocative movement of said bottom. The frame 22 is supported by suitable legs 30 which are vertically adjustable whereby the frame may be raised or lowered so as to aline the feed bottom 28 with the furnace door opening. The bottom is reciprocated through a link that is connected with a slotted lever 31, which lever is fulcrumed upon a stud carried by one of the frame legs 30. Fitted in the slot of the lever is a pin 32 that projects from a crank disk 33, which crank disk is mounted upon a shaft 34, the shaft being journaled 25 in suitable bearings carried by the adjacent frame leg.

Motion is imparted to the shaft 34 through a sprocket-wheel 35 carried thereby, which sprocket-wheel is in link belt connection 35 with a sprocket wheel 35^a mounted upon a motor-shaft 36, the motor being of any suitable type and is preferably, as shown, secured to the under side of the locomotive cab floor for convenience and economy in space. When it is desired to remove the frame from its automatic stoking position relative to the feed door of the furnace this chain connection between the motor and shaft 34 can be readily detached by uncoupling the link in said chain. Power is transmitted to the crusher through a beveled pinion 36 that is secured to the shaft 34 and arranged to mesh with a beveled wheel 37 carried by one section 38^a of a tumbler-rod 38, the sections of the rod being coupled by a universal joint 39, one member of which is provided with a sleeve that is in telescopic union with a squared end of the tumbler-rod 38. The tumbler-rod section 38^a is journaled in a bracket 40 that is swiveled upon the end of shaft 34, the opposite end of the tumbler-rod being journaled in a similar bracket 40^a that is swiveled upon an end of the crusher shaft 10, to which shaft motion is imparted by meshed beveled gear wheels 41, 41^a.

From the foregoing description it will be understood that power from the motor to the crusher is transmitted through a flexible shaft connection which is sectional

whereby the connection between the tender and locomotive may be broken when desired, in which case the elevator or conveyer is swung backward and attached in any suitable manner to the tender and the 70 hopper mechanism can then be removed from its stoking position.

In some instances it is desirable to have access to the furnace while the stoker is in operation and in order to conveniently obtain such access, as previously stated, the side walls of the hopper can be readily swung downward for the purpose of inserting a hand tool, shovel or the like within the fire-box of the furnace. This can be 80 readily accomplished by lifting the strap 24 which serves to hold the hinged wings in their upright position.

While I have shown and described one specific driving gear for the various traveling parts, it should be understood that this driving gear can be varied in accordance with the design of any skilled mechanic without departing from the spirit of my invention and that for the crusher 90 shown a roller crusher may be substituted in some instances.

It is apparent from the foregoing description that the automatic stoker will deliver coal crushed to the desired sizes, and 95 in quantities desired, within the hopper, from which it is discharged over the grate by the reciprocating bottom and leveled by the stoker-head 29. The stoker head acts to distribute and level the coal by passing 100 back and forth over or through the coal which tends to pile up upon the grate at the feed door incidental to the discharge of said coal from the box-like hopper bottom 28 and thus the pile is constantly being topped and distributed.

I claim:

1. In a locomotive having a furnace provided with a feed opening and a detachable coal-tender; the combination of a stoker in 110 communication with the furnace feed opening, a forwardly and downwardly inclined bottom section for the tender, a forwardly and upwardly inclined bottom section in hinge connection with the first named bottom section, the forwardly and upwardly inclined bottom section being provided with a door-controlled feed opening, a coal crusher detachably secured to the tender under said upwardly inclined bottom section and in register with its feed opening, an endless coal feeding conveyer apron yieldably connecting the crusher and stoker, a motor carried by the locomotive, an endless belt drive gear connection between the 125 motor and stoker, and a tumbler-rod in gear connection with the stoker and crusher, whereby the same is driven.

2. In a locomotive having a furnace provided with a feed opening and a detach- 130

able coal-tender; the combination of a
stoker in communication with the furnace
feed opening, a forwardly and downwardly
inclined bottom section for the tender, a
forwardly and upwardly inclined bottom
section in hinge connection with the first
named bottom section, the forwardly and
upwardly inclined bottom section being
provided with a door-controlled feed open-
10 ing, a coal-crusher, a shaft journaled with-
in the coal crusher, a gear connection be-
tween the shaft and coal crusher mecha-
nism, a conveyer apron frame loosely
mounted upon said shaft the free end of

the conveyer apron frame being arranged to 15
rest upon the stoker, a motor carried by said
locomotive, a gear connection between the
motor and stoker, and a flexible gear con-
nection between the stoker and coal-crush-
ing mechanism.

In testimony that I claim the foregoing
I have hereunto set my hand at Milwaukee
in the county of Milwaukee and State of
Wisconsin in the presence of two witnesses.

ALEXANDER J. McMULLEN.
